HAROLD F. SHEPHERD, OF GROVE CITY, PENNSYLVANIA, ASSIGNOR TO BESSEMER GAS ENGINE COMPANY, OF GROVE CITY, PENNSYLVANIA, A CORPORATION OF PENNSYLVANIA.

METHOD OF CONTROLLING THE TEMPERATURE OF HOT PLATES FOR EXPLOSIVE-ENGINES.

1,258,155.

Specification of Letters Patent.

Patented Mar. 5, 1918.

Application filed November 25, 1916. Serial No. 133,370.

To all whom it may concern:

Be it known that I, HAROLD F. SHEPHERD, a citizen of the United States, residing at Grove City, in the county of Mercer and 5 State of Pennsylvania, have invented new and useful Improvements in Methods of Controlling the Temperature of Hot Plates for Explosive-Engines, of which the following is a specification.

10 This invention relates to the method of controlling the temperature of hot plates for explosive engines and the like and consists in certain improvements therein as will be hereinafter fully described and pointed 15 out in the claims.

In the so-called hot bulb engine, the plate is maintained at a temperature at which the explosive mixture will ignite. The temperature of the plate is controlled by the heat 20 produced in the hot bulb through the burning of the gases exploded in the running of the engine. This heat varies with the intensity of the explosion and a variation in the amount of gases burned and consequently the temperature of the plate varies. 25 This variation is objectionable. If the temperature is sufficient to give proper ignition at light loads the higher temperature incident to the burning of a greater amount of 30 gases for the heavier loads tends to crack the oil used in the mixture and this produces carbon or an objectionable residue. To obviate this difficulty several plans have been adopted, the usual one being to inject water 35 with the explosive mixture and vary the amount of water introduced sufficiently to control the temperature within working limits. This adds to the working parts of the engine and is not entirely satisfactory in its 40 results.

The present invention is designed to automatically control the temperature of the hot plate of the hot bulb so as to give it a proper ignition temperature and still prevent a very wide variation from this temperature. In carrying out my method I use 45 an apparatus shown in the accompanying drawing as follows: The figure is a central vertical section of an explosive engine 50 wherein 1 marks the cylinder, 2 the piston operating therein, 3 the cylinder head, 4 the water jacket for the head, 5 the ignition or combustion chamber and 6 the injector for introducing fuel or fuel and air.

The hot plate 7 is preferably arranged 55 opposite the injector 6 and above the combustion or ignition chamber. The plate forms one wall of a receptacle 8 which is arranged in a jacketed housing 9, the receptacle 8 being spaced at 10 from the walls of this housing 9, and thus insulated from it. The receptacle has a flange 11 which is seated on the outer face of the housing and clamped in position by a condensing head 12. The condensing head has a cavity 13 60 which is connected with the circulating pipes 14.

A liquid 16 is provided for the receptacle 8. This liquid fully covers the plate 7, the level being indicated by the line X. This 70 liquid has a vaporizing point at or above the ignition point of the explosive mixture. I have found sulfur which is a liquid at the temperatures to which it is here ordinarily subjected and which has a vaporizing point 75 of 446° centigrade at atmospheric pressure well adapted for the purpose. Mercury which has a vaporizing point at 360° centigrade may be used to advantage with some mixtures. 80

In the operation of the device the heat generated in the combustion chamber is communicated to the plate 7. This heat is absorbed by the liquid 16. So long as this heat is at or below the vaporizing point of 85 the liquid no vapor is formed and no heat is thus dissipated. Inasmuch as there is a very slight connection between the receptacle 8 and the surrounding walls it is evident that a very slight amount of heat can 90 be thus dissipated. As soon as the temperature rises above the boiling point of the liquid, vapor is formed and this vapor rising comes into contact with the condensing head or condenser 12 which is constantly 95 cooled by a circulating medium, such as water, introduced through one pipe 14 and discharged through the other. The liquid so condensed returns to the body of the liquid 16 and remains there until again vaporized through the absorption of sufficient heat from the plate to accomplish this. The space above the level X forms an insulating space between the condenser and the liquid. Consequently very little heat is directly dissipated. If the load on the engine is increased so that the heat communicated to the plate 7 is increased a greater amount 100 105

of vapor is formed and the condenser being of ample capacity to condense all the vapor that may be formed a greater amount of vapor is condensed and returned. If the 5 engine is running under light load so that a small amount of vapor is formed the amount of vapor coming in contact with the condensing plate is comparatively slight and a comparatively slight amount of heat is thus 10 dissipated. The temperature of the plate 7 is thus kept within very close limits at a uniform temperature which temperature is the most desirable one in accomplishing the purpose, that is to say, it must be high enough 15 to get a perfect ignition and low enough to prevent cracking of the oil and formation of carbon.

It may be desired to vary the temperature at which the plate is maintained and 20 this may be accomplished by putting the receptacle 8 under pressure. This can be accomplished by introducing air or a neutral gas through the pipe 15. This not only affords a convenient means for varying the 25 temperature at which the plate 7 is maintained but it also affords a convenient means for a utilization of different materials for the liquid 16 because the vaporizing point of different materials may be varied by 30 varying this pressure.

It will be understood that the condenser 12 may be a wall of the receptacle or may be at a point remote from the receptacle and connected therewith.

35 While I have shown and described a condenser operating on the vapor as a means of dissipating the heat from the liquid I do not wish to be limited to this means in carrying out the broadest phases of my invention.

40 An auxiliary hot plate 17 may be provided for starting the engine which may be heated with a torch or other means. The ignition will be affected through this plate 45 until the plate 7 has reached the proper temperature.

What I claim as new is:—

1. The method of controlling the temperature of hot plates for explosive engines 50 and the like which consists in absorbing the heat from the plate by a liquid having a vaporizing point at or above the ignition point of the explosive mixture ignited by the hot plate.

55 2. The method of controlling the temperature of hot plates for explosive engines and the like which consists in absorbing the heat from the plate by a liquid having a vaporizing point at or above the ignition 60 point of the explosive mixture ignited by the hot plate and dissipating the heat absorbed by the liquid.

3. The method of controlling the temperature of hot plates for explosive engines and the like which consists in absorbing the 65 heat from the plate by a liquid having a vaporizing point at or above the ignition point of the explosive mixture ignited by the hot plate and dissipating the heat absorbed by the liquid through the vaporization 70 of the liquid.

4. The method of controlling the temperature of hot plates for explosive engines and the like which consists in absorbing the 75 heat from the plate by a liquid having a vaporizing point at or above the ignition point of the explosive mixture ignited by the hot plate, dissipating the heat absorbed by the liquid through the vaporization of the liquid, condensing the vapor and re- 80 turning it to the liquid.

5. The method of controlling the temperature of hot plates for explosive engines and the like which consists in absorbing the 85 heat from the plate by a liquid having a vaporizing point at or above the ignition point of the explosive mixture ignited by the hot plate, dissipating the heat absorbed by the liquid through the vaporization of the liquid, condensing the vapor at a point 90 insulated from the liquid and returning it to the liquid.

6. The method of controlling the temperature of hot plates for explosive engines and the like which consists in absorbing the 95 heat from the plate by a liquid and automatically varying the application of the liquid to increase the absorption as the intensity of the explosion varies to maintain an approximately uniform temperature of 100 the hot plate.

7. The method for controlling the temperature of hot plates for explosive engines and the like subjected to temperatures varying with the variations in the explosions to 105 maintain a pre-determined temperature which consists in absorbing the heat from the plate by a liquid having a vaporizing point at the pre-determined temperature and dissipating the heat through the vapor.

8. The method of controlling the temperature of hot plates for explosive engines and the like subjected to temperatures varying with the variations in the explosions to 115 maintain a pre-determined temperature which consists in absorbing the heat from the plate by a liquid having a vaporizing point at the pre-determined temperature and dissipating the heat through the vapor and condensing the vapor and returning it to 120 the liquid.

In testimony whereof I have hereunto set my hand.

HAROLD F. SHEPHERD.
